ABSTRACT OF THE DISCLOSURE

Esters of certain benzyl compounds and chrysanthemic acid are useful as insecticides.

This invention relates to benzyl chrysanthemumates. In one of its more specific aspects, this invention relates to insecticidally active esters of certain benzyl compounds and chrysanthemic acid, which acid is also referred to as 2,2-dimethyl-3-(2-methylpropenyl) cyclopropanecarboxylic acid.

Among the most widely used insecticides today are the pyrethrins, the active principal of pyrethrum flowers (*Chrysanthemum cinerariaefolium*). Pyrethrins (which may be described as esters of chrysanthemic acid) have a high order of insecticidal activity, a low mammalian toxicity, and a range of desirable biological properties including rapid knock-down effect. However, the relatively high cost and the uncertain supply (due to economic and political factors) of pyrethrins have encouraged attempts to prepare synthetic insecticides which retain the desirable properties of pyrethrins. As a result, much research effort has been directed toward preparing compounds which have a structural similarity to pyrethrins; that is, such compounds are esters of chrysanthemic acid.

It is an object of this invention to provide new benzyl chrysanthemumates. It is a further object of this invention to provide insecticidally active esters of certain benzyl compounds and chrysanthemic acid. It is a further object of this invention to provide an insecticidal composition comprising insecticidally active benzyl chrysanthemumates and a solvent therefor. It is a still further object of this invention to provide a process for killing insects by contacting said insects with insecticidally active benzyl chrysanthemumates. Other objects of this invention will appear herein.

These and other objects are attained through the practice of this invention, at least one embodiment of which comprises providing benzyl chrysanthemumates having the general structure:

wherein each R and R¹ is hydrogen, alkyl having 1-6 carbon atoms, alkoxy having 2-6 carbon atoms, bromo, chloro, fluoro, trifluoromethyl, cyano, nitro- or sulfoxy; and R² is hydrogen, alkyl having 1-6 carbon atoms, alkoxy having 2-6 carbon atoms, bromo, chloro, fluoro, trifluoromethyl, cyano, nitro, sulfoxy, or SO₃R³, wherein R³ is alkyl having 1-6 carbon atoms, phenyl, p-nitrophenyl, chlorophenyl, dichlorophenyl, or alkylphenyl, wherein the alkyl has 1-6 carbon atoms; provided that when R² is hydrogen or methyl, each R and R¹ is alkyl having 2-6 carbon atoms, alkoxy having 2-6 carbon atoms, bromo, chloro, fluoro, trifluoromethyl, cyano, nitro, or sulfoxy.

Another embodiment of this invention provides an insecticidal composition comprising (A) an insecticidally effective amount of a benzyl chrysanthemumate having

2

the above general structure and (B) a solvent for the benzyl chrysanthemumate.

Another embodiment of this invention provides a process for killing insects, wherein said process comprises contacting said insects with an insecticidally effective amount of a benzyl chrysanthemumate having the above general structure.

In the definition of the above general structure, the term "alkyl having 1-6 carbon atoms" includes methyl, ethyl, n-propyl, isopropyl, n-butyl, isobutyl, sec-butyl, t-butyl, n-pentyl, and n-hexyl; the term "alkoxy having 2-6 carbon atoms" includes ethoxy, propoxy, pentoxy, and hexoxy; and the term "alkyl having 2-6 carbon atoms" includes ethyl, n-propyl, isopropyl, n-butyl, isobutyl, sec-butyl, t-butyl, n-pentyl, and n-hexyl.

Whenever used in this application, the term "chrysanthemic acid" will be understood to include the various isomers of such acid. An especially preferred isomer is d-trans chrysanthemic acid.

The compounds of this invention are named as "benzyl chrysanthemumates." for example:

is p-nitrobenzyl chrysanthemumate, and

is 2,6-diethoxybenzyl chrysanthemumate.

Specific examples of other benzyl chrysanthemumates encompassed by this invention include:

p-fluorobenzyl chrysanthemumate
p-trifluoromethylbenzyl chrysanthemumate
p-cyanobenzyl chrysanthemumate
2,6-dichlorobenzyl chrysanthemumate
2,6-dimethyl-4-nitrobenzyl chrysanthemumate
2,6-dichloro-4-nitrobenzyl chrysanthemumate
2,6-dichloro-4-nitrobenzyl chrysanthemumate (using the d-trans acid)
2,4,6-tribromobenzyl chrysanthemumate
2,4,6-tribromobenzyl chrysanthemumate (using the d-trans acid)

The benzyl chrysanthemumates of this invention exhibit good insecticidal activity toward insects and low mammalian toxicity and may be prepared by well-known esterification reactions, including:

(1) the reaction of a chrysanthemumyl halide (e.g., chloride, bromide) and the benzyl alcohol corresponding to the desired benzyl chrysanthemumate—for example, p-nitrobenzyl chrysanthemumate may be prepared by reacting chrysanthemumyl chloride and p-nitrobenzyl alcohol.

(2) the reaction of an alkyl (e.g., methyl, ethyl) chrysanthemumate and the benzyl alcohol corresponding to the desired benzyl chrysanthemumate—for example, p-nitrobenzyl chrysanthemumate may be prepared by reacting ethyl chrysanthemumate and p-nitrobenzyl alcohol.

(3) the reaction of an alkali metal (e.g., sodium, potassium) chrysanthemumate and the benzyl halide (e.g., chloride, bromide) corresponding to the desired benzyl chrysanthemumate—for example, p-nitrobenzyl chrysanthemumate may be prepared by reacting sodium chrysanthemumate and p-nitrobenzyl chloride.

(4) the reaction, in the presence of a catalytic amount of sulfuric acid, of chrysanthemumic acid and the benzyl alcohol corresponding to the desired benzyl chrysanthemumate—for example, p-nitrobenzyl chrysanthemumate may be prepared by reacting, in the presence of a catalytic amount of sulfuric acid, chrysanthemumic acid and p-nitrobenzyl alcohol.

(5) the reaction, in the presence of triethylamine, of chrysanthemumic acid and the benzyl halide (e.g., chloride, bromide) corresponding to the desired benzyl chrysanthemumate—for example, p-nitrobenzyl chrysanthemumate may be prepared by reacting, in the presence of triethylamine, chrysanthemumic acid and p-nitrobenzyl chloride.

The details of the above esterification reactions are well-known and need not be described herein.

An insecticidal composition is obtained when the composition contains from about .01 to about 20 percent, by weight, of a benzyl chrysanthemumate of this invention. A preferred amount is from about 0.1 to about 15 percent.

Minor amounts of other substances may be added to the insecticidal compositions of this invention in order to provide particular functional or esthetic effects. Examples of such substances are perfumes, corrosion inhibitors, buffering agents, wetting agents, ultraviolet radiation absorbers, fillers, flame retardants, antioxidants, emulsifiers, and disinfectants.

The insecticidal compositions of this invention may be formulated in a number of ways to permit convenient application by the user. For example, pressurized compositions may be formulated wherein the composition in the container is in the form of an oil-in-water emulsion, a water-in-oil emulsion, or a solution. Such pressurized compositions may be prepared to give space sprays or surface sprays. Pressurization can be accomplished with propellants known in the art, including liquifiable hydrocarbons (such as propane, butane, and isobutane), liquifiable fluorinated alkanes (such as dichlorodifluoroethane, difluoroethane, and tetrafluoroethane) and compressible inert gases (such as nitrous oxide, nitrogen, and carbon dioxide).

Pressurized solvent compositions may be prepared by dissolving the benzyl chrysanthemumate in a suitable solvent (such as acetone, ethanol, naphtha, kerosene, or mineral spirits) and then pressurizing with one of the above propellants.

Pressurized oil-in-water compositions may be prepared by emulsifying the benzyl chrysanthemumate and any other hydrophobic components in water and then pressurizing with one of the above propellants.

These insecticidal compositions can also be formulated for use in hand sprayers, pump sprayers, foggers, and the like. These non-pressurized compositions can be in the form of oil-in-water emulsions, water-in-oil emulsions, or solutions. Except for the omission of the propellant, the non-pressurized compositions are prepared similarly to the pressurized compositions.

When preparing insecticidal compositions, one or more additional insecticides may be used in combination with the benzyl chrysanthemumates of this invention. Examples of such additional insecticides include pyrethrins, synthetic pyrethrins, and carbamates.

Examples of synthetic pyrethrins are 5-benzyl-3-furylmethyl-d,l-trans-chrysanthemumate (available from S. B. Penick Division, Corn Products Co.) and the other insecticidal esters of chrysanthemumic acid described in U.S. Pat. 3,465,007; allethrin (available from McLaughlin Gormley King Company); phthalthrin (available from Sumitomo Chemical Company under the trademark Neopyramin); and Dimethrin (available from McLaughlin Gormley King Company). Allethrin is the common name for the d,l - 2-allyl - 4-hydroxy-3-methyl-2-cyclopenten-1-one ester of cis- and trans-d,l-chrysanthemumic acid. Phthalthrin is the common name for N-(3,4,5,6-tetrahydrophthalimido)-methyl chrysanthemumate. Dimethrin is

a trademark for the ester of 2,4-dimethylbenzyl alcohol and chrysanthemumic acid.

Examples of the carbamate insecticides are 2-isopropoxyphenyl-N-methylcarbamate (sold by Chemagro under the trademark Baygon) and the carbamates described in U.S. Pat. 3,362,871.

In addition, increase in insecticidal activity may be attained by combining the benzyl chrysanthemumates of this invention one or more synergists. Examples of preferred synergists include dipropargyl phenylphosphonate, safrole (4 - propenyl - 1,2-methylenedioxybenzene), dihydro-safrole (4 - n - propyl-1,2-methylenedioxybenzene), piperonyl butoxide, and derivatives thereof.

Synergistic insecticidal compositions are obtained in accordance with this invention when the weight ratio of the insecticide portion to the synergist portion is from about 1:1 to about 1:10.

This invention will be further illustrated by the following examples of preferred embodiments. However, it will be understood that these examples are included for purposes of illustration and are not intended to limit the scope of this invention.

In the following examples, the term 'LD₅₀' refers to that amount, expressed in micrograms per insect, required to kill 50 percent of the insects treated.

EXAMPLE 1

An insecticidal composition is prepared by dissolving 0.1 gram of p-fluorobenzyl chrysanthemumate in 10 ml. of ethanol. Bioassays that establish the female housefly mortalities are conducted by applying 0.5 microliters of the composition on the insect's ventral abdomen. Each test is replicated twice with 25 female houseflies that have been anesthetized with carbon dioxide. Mortality readings are recorded 24 hours after the initial treatment. By this procedure, a compound is considered insecticidal if the LD₅₀ is 10 or less.

The LD₅₀ of p-fluorobenzyl chrysanthemumate is 5.12.

EXAMPLE 2

The procedure of Example 1 is repeated except that p-fluorobenzyl chrysanthemumate is replaced with other benzyl chrysanthemumates as indicated. The following results are obtained:

	LD ₅₀
p-Nitrobenzyl chrysanthemumate	1.24
p-Trifluoromethylbenzyl chrysanthemumate	1.58
p-Cyanobenzyl chrysanthemumate	3.10
2,6-dichlorobenzyl chrysanthemumate	.89
2,6-dimethyl - 4 - nitrobenzyl chrysanthemumate	.17
2,6-dichloro - 4 - nitrobenzyl chrysanthemumate	.14
2,6 - dichloro-4-nitrobenzyl chrysanthemumate (using the d-trans acid)	.06
4-nitro-6-chlorobenzyl chrysanthemumate	.47
2-chloro-6-nitrobenzyl chrysanthemumate	7.90
2 - chloro - 6 - nitrobenzyl chrysanthemumate (using the d-trans acid)	6.69
2,4,6-tribromobenzyl chrysanthemumate	.67
2,4,6-tribromobenzyl chrysanthemumate (using the d-trans acid)	.30

Although this invention has been described in detail with particular reference to preferred embodiments thereof, it will be understood that variations and modifications can be effected within the spirit and scope of this invention as described hereinabove and as defined in the appended claims.

I claim:

1. A benzyl chrysanthemumate selected from the group consisting of
  - 2,6-dichlorobenzyl chrysanthemumate
  - 2,6-dimethyl-4-nitrobenzyl chrysanthemumate
  - 2,6-dichloro-4-nitrobenzyl chrysanthemumate

the d-trans isomer of 2,6-dichloro-4-nitrobenzyl chrysanthemumate

4-nitro-6-chlorobenzyl chrysanthemumate

2,4,6-tribromobenzyl chrysanthemumate and
the d-trans isomer of 2,4,6-tribromobenzyl chrysanthemumate.

2. As defined by claim 1, the compound 2,6-dichlorobenzyl chrysanthemumate.

3. As defined by claim 1, the compound 2,6-dimethyl-4-nitrobenzyl chrysanthemumate.

4. As defined by claim 1, the compound 2,6-dichloro-4-nitrobenzyl chrysanthemumate.

5. As defined by claim 1, the compound the d-trans isomer of 2,6-dichloro-4-nitrobenzyl chrysanthemumate.

6. As defined by claim 1, the compound 4-nitro-6-chlorobenzyl chrysanthemumate.

7. As defined by claim 1, the compound 2,4,6-tribromobenzyl chrysanthemumate.

8. As defined by claim 1, the compound the d-trans isomer of 2,4,6-tribromobenzyl chrysanthemumate.

UNITED STATES PATENT OFFICE
CERTIFICATE OF CORRECTION

Patent No. 3,792,079 Dated February 12, 1974

Inventor(s) Vincent T. D'Orazio

It is certified that error appears in the above-identified patent and that said Letters Patent are hereby corrected as shown below:

Column 1, line 59, "nitro-" should be "nitro"
Column 2, lines 19, 49 and 52, and Column 4, lines 55, 59 and 62,
"trans" should be italicized.

Column 2, line 26, "NO" should be "NO₂"
Column 3, line 53, "non-perssurized" should be "non-pressurized"
Column 3, line 64, "d, 1-trans" should be italicized
Column 3, line 72, "d, 1" should be italicized
Column 3, line 73, "cis" and "trans-d, 1" should be italicized
Column 4, line 9, "with" should be inserted after "invention"
Column 4, line 23, " 'LD50' " should be " "LD50" "
Column 4, line 33, "housefles" should be "houseflies"

Claim 1, lines 6 and 10, Claim 5, line 1, and Claim 8, line 1, "trans"
should be italicized.

Signed and sealed this 17th day of September 1974.
